UNITED STATES PATENT OFFICE.

HOWARD HUBBARD, OF DILL, OKLAHOMA.

VENDING MACHINE.

Application filed October 27, 1922. Serial No. 597,363.

To all whom it may concern:

Be it known that I, HOWARD HUBBARD, a citizen of the United States, and a resident of Dill, in the county of Washita and State 5 of Oklahoma, have invented certain new and useful Improvements in Vending Machines, of which the following is a specification.

My present invention relates generally to vending machines, and more particularly to 10 machines for dispensing pencils, cigars and objects of like nature, and one adapted to vending of various other articles with but slight change, my primary object being the provision of a simple inexpensive check or 15 coin controlled mechanism by means of which a comparatively simple inexpensive vending machine as a whole may be produced and one which at the same time will be effective and efficient to defeat improper 20 withdrawals.

In the accompanying drawings which 25 illustrate my present invention and form a part of this specification,

Figure 1 is a perspective view of the 25 vending machine as a whole,

Figure 2 is a central vertical longitudinal section taken therethrough on line 2—2 of Figure 3,

Figure 3 is a horizontal section taken on 30 line 3—3 of Figure 2,

Figure 4 is a vertical transverse section taken on line 4—4 of Figure 2,

Figure 5 is an enlarged section through 35 a portion of the machine taken approximately on line 5—5 of Figure 3, showing the parts in normal position.

Figure 6 is a view similar to Figure 5 with the parts in position at the start of 40 movement of the dispensing slide or plunger after introduction of a coin,

Figure 7 is another similar view showing the slide farther advanced toward the point at which the coin is dropped,

Figure 8 is another similar view showing 45 the full advanced position of the slide ready to start upon its rearward movement, and

Figure 9 is a detail perspective view of the handle of the plunger or slide removed.

Referring now to these figures and particularly to Figures 1 and 2 my invention 50 proposes the employment of a rectangular casing generally indicated at 10, which may be formed of sheet metal, with a transverse slot 11 in the forward portion of its top 12 providing for introduction of pencils, cigars 55 and the like into the upper section of the

casing and into the article hopper 13 formed within said upper section of the casing above a horizontal stationary slide or plunger supporting plate 14.

The upper portion of the front wall 15 may have a transparent section 16 in order to permit of view of the articles within the hopper 13 and the lower section of this front wall has a slot 17 through which the articles may be withdrawn after they are dispensed downwardly through the dispensing aperture 18 of the plate 14 from which they fall upon a downwardly and forwardly inclined discharge plate 19, the latter located 70 within the lower section of the casing 10 and forming at the rear of this lower section a coin compartment 20. The casing preferably has a lower rear normally locked door 21 affording access to the coin compartment 20.

Slidably disposed in flatwise relation upon the supporting plate 14 is the slide or plunger 22, which is shiftable forwardly and rearwardly by virtue of a forwardly 80 extending rod 23 projecting forwardly through an aperture in the front wall 15 and having a curved front end 24, this rod forming a handle for the slide so that the latter may be moved forwardly by pulling on the handle until its dispensing aperture 25 comes beneath the lower mouth 26 of the hopper, and also moved rearwardly to the rear position where aperture 25 aligns vertically 85 with the dispensing aperture 18 of the supporting plate 14.

Rearwardly of its dispensing aperture or slot 25, the slide or plunger 22 has a coin receiving aperture 27 and in the rearmost or normal position of the slide or plunger, this coin receiving aperture is aligned beneath the inner lower end of the coin chute 28, whose upper outer end 29 opens through the upper portion of one side wall of the casing 10 as seen in Figures 1 and 4 and whose said lower inner portion has a recess 30 as seen in Figure 3 which provides for the casting out of coins of a smaller size than those contemplated for the proper actuation of the dispensing mechanism.

At the rear of its dispensing aperture or slot 18, the supporting plate 14 has an opening 31 longitudinally aligned with the coin receiving aperture 27 of the slide and positioned forwardly beyond the latter when the slide 22 is in its rearmost position so that the latter, with a coin in its aperture 27,

must travel forwardly a slight distance before the coin so held by the slide can drop through the opening 31 of the supporting plate 14 and into the coin chamber 20.

- 5 In order to normally hold the slide or plunger 22 against forward movement, a hook 32 normally extends downwardly through the alined dispensing apertures 25 of the slide and 18 of the supporting plate 10 as best seen in Figure 5, this hook 32 being formed upon one end of the forwardly projecting arm 33 of a coiled wire body 34, the latter being fixed upon a transverse shaft 35 whose opposite ends are loosely 15 disposed in bearing boxes 36 supported by the inner surfaces of the side walls 37 of the casing 10 as seen in Figures 2, 3 and 4 in particular, whereby the shaft coacts with the coiled body thereon in the formation of a latch. At its opposite end the coiled body 34 has a depending arm 38 which as seen in Figure 3 and in Figures 20 5 to 8 inclusive, depends through the coin receiving aperture 27 of the slide 22, and 25 also through the coin releasing aperture 31 of the supporting plate 14, it being thus positioned for engagement by a coin 39 disposed in the coin receiving aperture 27 of the slide.
- 30 It is obvious from an inspection of Figure 5 that with the parts in normal position the hook 32 of the latch prevents the slide 22 from being shifted forwardly and it will be observed from this figure that 35 the slide is normally held in its rearmost position by means of a spring 40 attached at its forward end to the slide and at its rear end to the rear wall 41 of the casing so that the slide is thus maintained in position to receive a coin 39 through the coin 40 chute 28 and within the coin receiving aperture 27 of the slide forwardly of the depending arm 38 of the latch. With the coin in position as just described, the operator by grasping the handle 24 can shift the slide 22 forwardly because of the engagement of the coin 39 as seen in Figure 45 6 with the arm 38 so as to thus rock the latch and lift the hook 32 above the slide 50 22. As forward movement of the slide continues and the coin reaches the opening 31 of plate 14, the coin upon falling as shown in dotted lines in Figure 7 releases the latch but as the slide has then progressed to a 55 point where its dispensing aperture 25 is forwardly of the hook 32 the latter simply drops upon the surface of the slide and the slide is free for a continuance of its forward movement until its dispensing aperture 25 60 is below the mouth 26 of the hopper 13 from which it receives its supply of pencils,

cigars or other articles. At this point it is to be noted that while the aperture 25 is shown in Figure 8 as receiving three of the pencils or other articles, the number 65 of articles dispensed at each operation is controlled by the dimensions of the aperture 25 and it thus becomes quite obvious that one, two or three articles may be dispensed at a time as may be desired. 70

After having drawn the handle 24 forwardly to the full extent of movement of the slide, it is then shifted rearwardly, or if released will move rearwardly under tension of spring 40. 75

I claim:

1. A vending machine including a manually shiftable slide having an article receiving slot and a coin receiving aperture, a magazine opening downwardly upon the slide, a stationary supporting plate on which the slide is shiftable, having a slot with which the said slot of the slide is normally registered, and having a coin releasing aperture with which the coin receiving aperture of the slide is registrable upon forward movement of the slide, and a controlling member mounted to swing vertically above the rear portion of the slide, having a hook depending through said slots of the slide and its supporting plate to hold the slide from movement, and also having an arm normally depending through the forward portion of the coin receiving aperture of the slide for engagement and actuation by a coin within said aperture. 90

2. A vending machine including a manually shiftable slide having an article receiving slot and a coin receiving aperture, a magazine opening downwardly upon the slide, a stationary supporting plate on which the slide is shiftable, having a slot with which the said slot of the slide is normally registered, and having a coin releasing aperture with which the coin receiving aperture of the slide is registrable upon forward movement of the slide, and a controlling member mounted to swing vertically above the rear portion of the slide, having a hook depending through said slots of the slide and its supporting plate to hold the slide from movement, and also having an arm normally depending through the forward portion of the coin receiving aperture of the slide for engagement and actuation by a coin within said aperture, said controlling member having a coiled body, and a cross bar above the rear portion of the slide on which the said coiled body of the controlling member is mounted. 110
